SCAVENGING FOR TWO-STROKE CYCLE
ENGINES

Herman Theodor Pyk, Saltsjö-Duvnäs, and Hilding Gunnar Camner, Storangen, Sweden, assignors to Aktiebolaget Atlas Diesel, Sickla, near Stockholm, Sweden, a corporation of Sweden

Application April 6, 1945, Serial No. 586,918
In Sweden April 18, 1944

7 Claims. (Cl. 123—65)

1

This invention relates to improvements in the scavenging system of two stroke cycle internal combustion engines. One object of the invention is to improve the efficiency of the scavenging of the combustion cylinders in engines with doubleflow as well as uniflow scavenging.

For this and other purposes we provide in a two stroke cycle internal combustion engine, a combustion cylinder, two scavenging fluid passages ending each per se in an opening in one half of said cylinder and disposed symmetrically one on each side of an axial centre plane through said cylinder half and directed towards said centre plane, a wall in each one of said passages radially confining the passage on its outside and extending substantially tangentially to the cylinder and making a sharp turn towards the central portion of the cylinder half close to an axial confining edge of said pertaining opening, and a portion of said wall disposed adjacent the leading peripheral edge of the opening inclined an angle towards the cylinder axis decreasing towards said sharp turn, so that the scavenging fluid entering the opening is directed most axially in the cylinder in the vicinity of the sharp turn.

This arrangement of the scavenging passages has resulted in a very advantageous distribution and effective filling of said cylinder half with scavenging fluid. In engines with doubleflow scavenging the combustion gases are then obviously at first displaced from said cylinder half and when said displacement is substantially finished and the scavenging fluid reaches the other cylinder end an extension of the scavenging fluid to the rest of the cylinder and a simultaneous displacement of the combustion gases from this part of the cylinder takes place. In engines with uniflow scavenging each cylinder half is filled substantially separately with scavenging fluid without any considerable mixture of scavenging fluid and combustion gases in one cylinder half with the scavenging fluid and the combustion gases in the other cylinder half. The sharp turn of the outside walls of at least two scavenging fluid passages and the decreasing angle between portions of said walls near the leading peripheral edge of the scavenging openings and the cylinder axis towards said sharp turn result in axially directed fluid streams in the vicinity of the cylinder wall, which obviously have an important influence on the scavenging of the peripheral portions of the cylinder and counteract the formation of peripheral combustion gas whirls which in a high degree reduce the scavenging efficiency. However, the invention is not

limited to a scavenging process occurring in the manner herein described. One advantage of the invention is that a large effective scavenging opening area is obtained without reduction of the exhaust port area. In the accompanying drawings some embodiments of the invention are illustrated by way of example, which, however, are by no means limiting for the invention, which may be employed in engines in which the scavenging fluid is air only or air admixed with the combustible.

Fig. 1 is a cross section of a cylinder of an engine with doubleflow scavenging the section being taken through the scavenging and exhaust ports. Fig. 2 is a similar cross section of the cylinder half in which the scavenging openings are disposed of a similar engine cylinder. Figs. 3, 4, 5 and 6 are partial axial sections of the engine cylinders according to Figs. 1 and 2 on lines III—III, IV—IV, V—V and VI—VI, respectively, in Figs. 1 and 2. Fig. 7 is a cross section of a cylinder of an engine with uniflow scavenging the section being taken through the scavenging ports. Fig. 8 is a similar cross section through the scavenging openings in the cylinder of a further engine with uniflow scavenging. Figs. 9 and 10 are partial axial sections on lines IX—IX and X—X, respectively, in Figs. 7 and 8.

The engine cylinder 1 illustrated in cross section in Fig. 1 is intended for an engine with doubleflow scavenging through piston controlled scavenging and exhaust openings at one end of the working cylinder. The cross section is taken on a plane which in the lower end position of the piston touches the top of the piston and extends through the scavenging and exhaust openings. Scavenging air is supplied to the working cylinder from one side of the engine through scavenging air supply passages 2, 3 one on each side of the cylinder and four scavenging air passages 4, 5, 6 and 7 leading to the cylinder half which is hatched with dotted lines in Fig. 1. The passages 4, 5, 6 and 7 are disposed symmetrically around the centre plane 8 of the hatched cylinder half. The passages 4—7 are inclined with regard to the cylinder axis and direct the scavenging air entering the cylinder away from the top of the piston 9 controlling the scavenging openings as obvious from Figs. 3—6. Furthermore, the piston 9 is provided with a properly chamfered portion 10. The engine cylinder 1 is provided with a separate cylinder liner 11. The exhaust passages 12 extend from the not hatched cylinder half of Fig. 1.

The side of the scavenging passages 4 and 5 dis-

posed nearest the intersection between the centre plane 8 and the periphery of the hatched cylinder half is confined radially by walls 13, 14 extending at first almost tangentially to the hatched cylinder half and making just before the axially extending inlet edge of the pertaining scavenging opening a sharp turn of about 90° forming surfaces 15, 16 directed parallel to the centre plane 8 as indicated by the line 17. Said surfaces 15, 16 are formed completely in the material of the liner 11. Portions 18, 19 of the wall 13 of the passage 4 nearest the leading peripheral edge of the scavenging opening are inclined an angle towards the cylinder axis which decreases as the wall 13 approaches the sharp turn and the surface 15, as illustrated in Figs. 5 and 6. The symmetrically situated wall 14 of the passage 5 is formed in the same way as the wall 13. The radial depth of the passages 4 and 5 also decreases towards the surfaces 15, 16 in the direction of the scavenging air flow, as illustrated in Figs. 5 and 6, resulting in an increased scavenging air velocity in this portion of the passages. This increased velocity together with the reduced angle between the wall portion 19 and the cylinder axis results in more axially directed air streams from the portion of the scavenging passages 4, 5 close to the sharp turn than from other portions of the passages, as indicated by the arrows 20 and 21 in Figs. 5 and 6.

The scavenging air passages 6 and 7 are confined at the side nearest the intersection between the centre plane 8 and the periphery of the hatched cylinder half by walls 22, 23 extending at first substantially tangentially to the hatched cylinder half and making just before the axially extending inlet edge of the pertaining scavenging opening a sharp substantially 90° turn forming surfaces 24, 25 directed towards the central cylinder portion, as indicated by the line 26. The wall 22 of the passage 6 has wall portions 27 and 28 close to the leading peripheral edge of the pertaining scavenging opening which, as obvious from Figs. 3 and 4, are inclined an angle towards the cylinder axis which decreases as the wall 22 approaches the sharp turn and the surface 24. The symmetrically situated passage 7 has a wall 23 shaped in the same way. Furthermore, as obvious from Figs. 3 and 4, the radial depth of the passages 6 and 7 decreases materially towards the surfaces 24, 25 in the direction of flow of the scavenging air. The described arrangement results in an increased scavenging air velocity in the passages 6, 7 close to the surfaces 24, 25 and said velocity together with the reduced angle of inclination towards the cylinder axis of the wall portion 28 results in more axially directed air streams from the portions of the scavenging passages 6, 7 close to the sharp turn than from other portions, as indicated by the arrows 29 and 30 in Figs. 3 and 4.

The strong almost axial air streams obtained from the spaces just in front of the surfaces 15, 16 and 24, 25 are apparently the cause of the important improvement of the scavenging efficiency observed during tests with the invention. At least partly, this appears to depend upon the fact that peripheral combustion gas whirls or congestions in the cylinder half, into which the scavenging air is admitted, are avoided.

Fig. 2 is a partial cross section of a cylinder of an engine with doubleflow scavenging according to a modification of the embodiment illustrated in Fig. 1 differing from said embodiment in a few details only. The same reference nu-

mersals as in Fig. 1 have therefore been used to indicate similar parts and the differing parts only are described hereinbelow. The difference consists in this that the walls 13, 14 confining the passages 4 and 5 radially at the outside just before the axial inlet edge of the pertaining scavenging opening make a sharp turn forming surfaces 31, 32 directed as indicated by the line 33 towards a point of the centre plane 8 situated on one third of the radius from the periphery of the cylinder. The walls 22, 23 of the passages 6, 7 make a similar sharp turn as the corresponding walls in Fig. 1 forming surfaces 34 and 35 at the axial inlet edge of the pertaining scavenging opening directed as indicated by the line 36 towards substantially the same portion of the centre plane 8 as the surfaces 31, 32. Figs. 3-6 also illustrate partial axial sections of the passages 4 and 6 in Fig. 2.

Figs. 7 and 8 are cross sections of cylinders 37 and 38, respectively, of engines with uniflow scavenging from an inlet at one end of the working cylinder to an outlet at the opposite end. In these embodiments scavenging air is supplied through scavenging air supply conduits 39, 40 and 41, 42, respectively, at two sides of the engine cylinders. Scavenging air is conducted from the scavenging air supply conduits 39, 40 through passages 43, 44, 45 and 46 to the hatched cylinder half in Fig. 7 symmetrically with reference to an axial centre plane 47 of said cylinder half. The passages 43-46 are directed away from the piston 48 controlling the scavenging openings. The piston may be chamfered correspondingly as indicated at 49 in Figs. 9 and 10. The outside walls 50-53 of the passages 43-46 which are substantially tangential to the hatched cylinder half and situated nearest the intersection between the periphery of said cylinder half and the centre plane 47 make a sharp turn just before the axial inlet edge of the pertaining scavenging openings forming surfaces 54-57 directed parallel with the centre plane and towards the central portion of the hatched cylinder half, respectively. The portions 58, 59 of the walls 50-53 situated nearest the leading peripheral edge of the scavenging openings are inclined an angle towards the cylinder axis which decreases towards the surfaces 54-57 as obvious from Figs. 9 and 10. The surfaces 54-57 are formed in the cylinder liner 60. In the vicinity of the surfaces 54-57 the air entering the cylinder is directed more axially than the air entering through the remaining portion of the pertaining scavenging opening, as previously described in connection with the embodiments according to Figs. 1 and 2.

The not hatched cylinder half in Fig. 7 is carried out as a converted image of the shaded cylinder half and is therefore not described in detail. Both cylinder halves operate with axial scavenging and to a large extent independently of each other so that the air and gases in one cylinder half do not mix with the air and gases of the other cylinder half during the scavenging period.

In the embodiment according to Fig. 8 the scavenging air supply conduit 41 is connected to four scavenging air passages 61, 62, 63, 64 deflecting the scavenging air and directed towards an axial centre plane 65 of the hatched cylinder half in Fig. 8. Walls 66-69 of the scavenging air passages 61-64 situated nearest the intersection between the centre plane 65 and the periphery of the hatched cylinder half make

a sharp turn just before the axial inlet edge of the pertaining scavenging openings forming surfaces 70-73 directed towards a portion of the centre plane 66 within the hatched cylinder half situated near the middle of the cylinder radius. The surfaces 70-73 are formed in the cylinder liner 14. The portions 58, 59, Figs. 9 and 10, of the walls 66-69 disposed nearest the leading peripheral edge of the scavenging openings are inclined an angle towards the cylinder axis which decreases towards the surfaces 70-73, respectively, so that in this case also strong axial air streams are obtained in the spaces near said surfaces.

The not hatched cylinder half of Fig. 3 is carried out as a converted image of the hatched cylinder half and is not described.

The embodiments of the invention above described and illustrated in the drawings should only be considered as examples and the invention may be modified in several different ways within the following claims. For instance, the number of scavenging air passages leading to the different cylinder halves may be larger or smaller than illustrated. The cylinders may furthermore be carried out without separate liners.

What we claim is:

1. In a two stroke cycle internal combustion engine, a combustion cylinder, at least one working piston in said cylinder, inlet openings in the cylinder controlled by said piston, at least two scavenging fluid passages each ending in at least one of said openings in one half of said cylinder and disposed symmetrically on each side of an axial centre plane through said cylinder half and directed towards said centre plane, a wall in each one of said passages radially confining the passage on its outside and extending substantially tangentially to the cylinder and making a sharp turn towards the central portion of the cylinder half close to the axial confining edge of a pertaining opening, and a portion of said wall disposed adjacent the leading peripheral edge of said opening inclined at an angle towards the cylinder axis decreasing towards said sharp turn, so that the scavenging fluid entering said opening is directed most axially in the cylinder in the vicinity of the sharp turn.

2. In a two stroke cycle internal combustion engine, a combustion cylinder, a working piston in said cylinder, inlet openings in the cylinder controlled by said piston, two scavenging fluid passages each ending in at least one of said openings in one half of said cylinder and disposed symmetrically on each side of an axial centre plane through said cylinder half nearest the intersection between said centre plane and the periphery of the cylinder half and directed away from the piston towards the centre plane, two further scavenging fluid passages each ending in at least one of the openings in the cylinder half and disposed symmetrically on each side of the axial centre plane second nearest said intersection and directed away from the piston towards the centre plane, a wall in each one of said passages radially confining the passage on its outside and extending substantially tangentially to the cylinder and making a sharp turn towards the central portion of the cylinder half close to the axial confining edge of a pertaining opening nearest the intersection, and a portion of said wall disposed adjacent the leading peripheral edge of said opening inclined at an angle towards the cylinder axis decreasing towards said sharp turn, so that the scavenging fluid entering said opening

is directed most axially in the cylinder in the vicinity of the sharp turn.

3. In a two stroke cycle internal combustion engine, a combustion cylinder, a working piston in said cylinder, inlet openings in the cylinder controlled by said piston, two scavenging fluid passages each ending in at least one of said openings in one half of said cylinder and disposed symmetrically on each side of an axial center plane through said cylinder half and directed away from said piston towards said centre plane, a wall in each one of said passages radially confining the passage on its outside and extending substantially tangentially to the cylinder and making a sharp turn close to the axial confining edge of a pertaining opening nearest the intersection between the centre plane and the periphery of the cylinder half towards a portion of the centre plane within the cylinder half between the cylinder axis and two thirds of the radius from said axis, and a portion of said wall disposed adjacent the leading peripheral edge of said opening inclined at an angle towards the cylinder axis decreasing towards said sharp turn, so that the scavenging fluid entering said opening is directed most axially in the cylinder in the vicinity of the sharp turn.

4. In a two stroke cycle internal combustion engine, a combustion cylinder, a working piston in said cylinder, inlet openings in the cylinder controlled by said piston, two scavenging fluid passages each ending in at least one of said openings in one half of said cylinder and disposed symmetrically on each side of an axial centre plane through said cylinder half and directed away from said piston towards said centre plane, a cylinder liner, a wall in each one of said passages radially confining the passage on its outside and extending substantially tangentially to the cylinder and making a sharp turn towards the central portion of the cylinder half close to the axial confining edge of a pertaining opening and formed in said liner at least after said sharp turn, and a portion of said wall disposed adjacent the leading peripheral edge of said opening inclined at an angle towards the cylinder axis decreasing towards the sharp turn, so that the scavenging fluid entering said opening is directed most axially in the cylinder in the vicinity of the sharp turn.

5. In a two stroke cycle internal combustion engine, a combustion cylinder, two scavenging fluid passages each ending in an opening at one end of a first half of said cylinder and disposed symmetrically one on each side of an axial centre plane through said cylinder half and directed towards said centre plane, a wall in each one of said passages radially confining the passage on its outside and extending substantially tangentially to the cylinder and making a sharp turn towards the central portion of the cylinder half close to an axial confining edge of said pertaining opening, a portion of said wall disposed adjacent the leading peripheral edge of the opening inclined at an angle towards the cylinder axis decreasing towards said sharp turn, so that the scavenging fluid entering the opening is directed most axially in the cylinder in the vicinity of the sharp turn, a second cylinder half provided with scavenging fluid passages formed as a mirror image of the first cylinder half, and an outlet at the opposite end of the combustion cylinder.

6. In a two stroke cycle internal combustion engine, a combustion cylinder, a reciprocating piston in said cylinder, two scavenging fluid pas-

sages each ending in an opening in one half of said cylinder controlled by said piston and disposed symmetrically one on each side of an axial centre plane through said cylinder half and directed away from the piston towards said centre plane, a wall in each one of said passages radially confining the passage on its outside and extending substantially tangentially to the cylinder and making a sharp turn towards the central portion of the cylinder half close to an axial confining edge of the pertaining opening, and a portion of said wall disposed adjacent the leading peripheral edge of the opening inclined at an angle towards the cylinder axis decreasing towards said sharp turn, so that the scavenging fluid entering the opening is directed most axially in the cylinder in the vicinity of the sharp turn.

7. In a two stroke cycle internal combustion engine, a combustion cylinder, scavenging openings in one half of said cylinder, a reciprocating piston in the cylinder controlling said openings, two scavenging fluid passages each ending in a scavenging opening and disposed symmetrically one on each side of an axial centre plane through said cylinder half nearest the intersection between said centre plane and the periphery of the cylinder half and directed away from said piston in a plane substantially perpendicular to the centre plane, two further scavenging fluid passages each ending in a scavenging opening in the cylinder half and disposed symmetrically one on each side of the axial centre plane second nearest said intersection and directed away from the piston and

the other cylinder half towards the centre plane, a wall in each one of first-mentioned two passages radially confining the passage on its outside and extending substantially tangentially to the cylinder and making a sharp turn towards the central portion of the cylinder close to an axial confining edge of the pertaining scavenging opening nearest the intersection, and a portion of said wall disposed adjacent the leading peripheral edge of the opening inclined at an angle towards the cylinder axis decreasing towards said sharp turn, so that the scavenging fluid entering the opening is directed most axially in the cylinder in the vicinity of the sharp turn.
